United States Patent Office

Des. 191,383
Patented Sept. 19, 1961

191,383

UNITARY MOTOR BOAT DECK

Frederick S. Brennan, Evanston, Ill., assignor to Textron Inc., Providence, R.I., a corporation of Rhode Island

Filed Feb. 6, 1959, Ser. No. 54,476

Term of patent 7 years

(Cl. D71—1)

FIG. 1.

FIG. 2.

FIG. 3.

FIG. 1 is a perspective view of a unitary motor boat deck showing my new design.

FIG. 2 is a side elevation thereof.

FIG. 3 is a top plan view thereof.

I claim:

The ornamental design for a unitary motor boat deck, as shown.
